UNITED STATES PATENT OFFICE.

CLAYTON MARK, OF LAKE FOREST, ILLINOIS, ASSIGNOR TO THE NATIONAL MALLEABLE CASTINGS COMPANY, OF CLEVELAND, OHIO, A CORPORATION OF OHIO.

JOURNAL-BOX.

1,278,969.

Specification of Letters Patent. Patented Sept. 17, 1918.

Original application filed November 8, 1913, Serial No. 779,941. Divided and this application filed March 16, 1915. Serial No. 14,659.

To all whom it may concern:

Be it known that I, CLAYTON MARK, a citizen of the United States, residing at Lake Forest, Lake county, Illinois, have invented 5 new and useful Improvements in Journal-Boxes, of which the following is a specification, reference being had to the accompanying drawings, in which—

Figure 1 is an elevation of a journal box 10 embodying my invention; Fig. 2 is a plan thereof partly broken away on lines II—II of Fig. 5; Fig. 3 is a section on lines III—III of Fig. 2; Fig. 4 is a partial rear elevation; Fig. 5 is a section on lines V—V 15 of Fig. 2, and Fig. 6 is a section on lines VI—VI of Fig. 2.

My invention relates to journal boxes, and consists in a journal box comprised of two or more parts, in which the top is preferably 20 made of cast metal and the bottom, or oil cellar, is preferably made of pressed or stamped metal, and in uniting these parts together by welding.

Various other features comprising my 25 invention are hereinafter described and claimed, the method, however, being claimed in my pending application, Serial Number 779,941, filed November 8, 1913, of which the present application is a division.

30 Referring to the drawings, A indicates the top of the journal box, preferably comprised of cast metal, such as malleable iron or steel, because of its somewhat intricate shape, and having the usual hinge lug 2, and 35 the journal bearing side stops 3. B indicates the bottom part or oil cellar, and C the dust guard wall, both of which are preferably made of pressed steel. The oil cellar B is preferably made without the usual 40 strengthened ribs, and with its top edges 4 unbroken, so that they bear directly against the underface of the top A.

Extending downwardly from the top A 45 are flanges 5, which are adapted to enter inside of the top edges 4 of the oil cellar B and to fit closely thereagainst. When these parts 4 and 5 are thus interengaged they are secured or bonded together by welding. The uniting of the parts may be effected by continuously welding together the contacting 50 faces of the flanges 5 and the top edges 4 between the points *a—a* and *b—b*, as is indicated in Fig. 2, or it may be done by “spot welding” at various points along these

faces. In either event the result is that the 55 top A and oil cellar B are made, in effect, into an integral structure. If desired, the parts may also be welded along the lines *c* and *d*.

The dustguard wall C fits closely in the 60 rear end of the oil cellar B and forms the inner wall of the dustguard chamber 9. The member C has inwardly-turned flanges 7 and 8 in its lower portion, which bear against the bottom and sides respectively, and in its 65 upper portion it has also outwardly-turned flanges 10, which bear against the sides of the oil cellar B. The member C may be welded to the top A and bottom B along the flanges 7, 8 and 10 where these flanges bear 70 against the inner surfaces of the bottom and side walls of the oil cellar B and come in contact with the top A.

One of the advantages of my invention is that by making the body of the box of 75 pressed or stamped metal the boxes can be made much lighter without necessitating any sacrifice in strength, and with a slight increase in the thickness of the metal the boxes may be made without the usual strengthening ribs. It is, however, not necessary that the bottom of the box be made to withstand 80 the strains to which the top is subjected, since normally the bottom acts merely as an oil cellar, practically all of the strains being transmitted through the top to the side frame, so that from considerations of lightness and cheapness the bottom may be made 85 of much lighter metal than the top.

If desired, the connection between the top 90 and the oil cellar may be made by butt welding the upper edges of the oil cellar against the under surface of the top, as is shown at *e* in Fig. 6, in which case the downwardly extending flanges will act as reinforcements 95 for the parts.

The terms and expressions herein used are used as terms of description and not of limitation, and I have no intention in the use of such terms and expressions to exclude any 100 mechanical equivalent for the features shown and described, but recognize that various structural modifications are possible within the scope of the invention claimed.

What I claim is:

1. A journal box comprised of a cast metal top, a pressed metal oil cellar, the rear wall thereof forming the outer wall for a dust-

guard slot, and an inner dust-guard wall, said wall being contained in the pressed metal oil cellar, and having flanges adapted to be secured to the oil cellar by welding, 5 said flanges having a bearing on the rear wall of the oil cellar, and determining the position of the inner dust-guard wall with relation to the rear wall of the oil cellar.

2. A journal box having its rear wall 10 forming the outer wall of a dust-guard slot, and an inner dust-guard wall, said wall be-

ing wholly contained in said box and having oppositely-directed flanges, one of the flanges determining the position of the inner wall with relation to the rear wall of the 15 box and another of the flanges serving as means for attaching the inner wall to the box.

CLAYTON MARK.
